HYDRAULIC POWER UNIT

Arthur G. Mellinger, Lancaster, Pa.

Application October 28, 1942, Serial No. 463,668

10 Claims. (Cl. 121—92)

This invention relates to a hydraulic power unit and has for an object to provide such a unit including a stator and a rotor constructed and assembled in a manner whereby fluid pressure is transformed effectively into rotary motion.

The invention also has for an object to provide a unit of this kind including a stator and a rotor and wherein said parts are provided with coacting abutments and wherein the abutments carried by the rotor are mounted for movement into effective or ineffective positions and wherein the fluid under pressure is employed to maintain such abutments in requisite positions during their periods of effectiveness.

The invention consists in the details of construction and in the combination and arrangement of the several parts of my hydraulic power unit whereby certain important advantages are attained, as will be hereinafter more fully set forth.

In order that my invention may be better understood, I will now proceed to describe the same with reference to the accompanying drawings, wherein:

Figure 1 is a sectional view with parts in elevation and of a diagrammatic character illustrating a power unit constructed in accordance with an embodiment of my invention.

Figure 2 is a fragmentary view in top plan of the valve structure as herein embodied.

Figure 3 is a sectional view taken substantially on the line 3—3 of Figure 1, looking in the direction of the arrows.

Figure 4 is an enlarged sectional view taken substantially on the line 4—4 of Figure 3.

Figure 5 is an enlarged detailed sectional view taken substantially on the line 5—5 of Figure 3.

Figure 6 is a sectional view taken substantially on the line 6—6 of Figure 1, looking in the direction of the arrows.

Figure 7 is an enlarged detailed sectional view taken substantially on the line 7—7 of Figure 6.

Figure 8 is a sectional view also taken substantially on the line 3—3 of Figure 1, with the rotor in fragment and diagrammatically indicated, a second position of the rotor fragment being indicated by broken lines.

Figure 9 is an enlarged detailed sectional view taken substantially on the line 9—9 of Figure 8.

Figure 10 is an enlarged detailed sectional view taken substantially on the line 10—10 of Figure 8.

Figure 11 is a view in perspective of one of the blocks 63 unapplied.

Figure 12 is a view in outer end elevation of said block.

Figure 13 is a view in perspective of a gate valve unapplied.

5 Figure 14 is a view in perspective of a back plate or block unapplied, and

Figures 15 and 16 are fragmentary sectional views illustrating a modified structure.

As disclosed in the accompanying drawings, S 10 denotes a stator including a head 1 of desired configuration and dimensions and which has a sleeve 2 at its axial center with the bore 3 of the sleeve disposed through the head 1. The outer or free end portion of the sleeve 2 is adapted to be

rigidly and nonrotatably anchored, as at 4, to a suitable support depending upon the character of the general assembly of which the power unit is a part. In Figure 1 of the drawings, the supporting member M is disclosed as a suitably held tubular member having an end portion snugly received within the outer portion of the bore 3 of the sleeve 2.

The wall of the sleeve 2 at the inner portion thereof is provided with the ports 5 and 6 spaced 15 apart in a direction lengthwise of the sleeve 2 but herein disclosed as in relatively close relation. One of these ports 5 or 6 serves as an outlet port when the other is being used as an inlet port, as will hereinafter be more particularly referred to.

20 These ports 5 and 6 have in communication therewith and leading therefrom the pipe lines or conduits 7 and 8 respectively which also have required communication with a valve structure V of the type embodied in Patent No. 2,178,182, which 25 issued October 31, 1939, and which valve structure allows for the reversing of the flow of the fluid to the ports 5 and 6.

It is to be stated at this time, however, that 30 in this valve structure the rotary valve members 9 are operatively connected, as at 10, for unitary rotation, and in such a manner that when one of the valve members 9 is opened with respect to the inlet of the valve structure, the other is closed and, of course, when one of said valve members

35 is in a position to close its associated exhaust, the other valve member is in open position with respect to its exhaust. It is by means of this valve structure that the rotor R of the unit may be caused to rotate as desired in either direction.

40 Threaded or otherwise tightly held within the bore 3 of the sleeve 2 outwardly of the ports 5 and 6 is a head or plate 11 which closes the bore of the sleeve 2 and the inner end of the bore 3 of the sleeve 2 is directly in communication with 45 the cylinder or bore 12 of material diameter and

depth provided in the outer face of the head 1 of the stator. The inner portion of the inner or base wall 14 of the cylinder or bore 12 at its communication with the bore 3 of the sleeve 2 is rabbeted, as at 15, to snugly accommodate a portion of a conventional ball bearing assembly 16 which is also snugly fitted upon an outstanding hub sleeve 17 comprised in the rotor R. This ball bearing assembly 16, as herein disclosed, is effectively maintained in applied or working position by an annular member 18 which is tightly but rotatably received within the inner or adjacent portion of the bore 3 of the sleeve 2.

The wall at said inner portion of the bore 3 of the sleeve 2 is provided therearound with a continuous groove or channel 19 concentric to the axial center of the bore 3 of the sleeve 2 and which groove or channel 19 registers with a surrounding groove or channel 20 provided in the periphery of the annular member 18. As herein disclosed, these grooves or channels 19 and 20 are substantially V-shaped in cross section with their apices inwardly disposed and which registering grooves or channels in the assembly of the parts snugly receive packing segments 21.

The side wall 22 of the cylinder or bore 12 of the head 1 is provided with the circumferentially disposed and relatively deep grooves 23, herein disclosed as two in number and suitably spaced in a direction axial of the head 1. These grooves 23 extend substantially entirely around the head 1 but are in reverse relation, as is clearly illustrated in Figures 3, 6 and 8 of the drawings. One of these grooves 23 is in use when the rotor R is rotating in one direction and the second groove 23 is in use when the rotor is rotating in the opposite direction. There is, however, no operative connection between the two grooves 23 as the functioning of one is entirely independent of the functioning of the other.

One end portion of each of the grooves 23 communicates with an outwardly disposed port 24 provided in the head 1 and in communication with this port 24 and leading therefrom is a pipe line or conduit 25 which is in communication with a port 26 or 27 disposed through the wall of the sleeve 2 and herein disclosed as diametrically opposed to the ports 5 and 6, respectively. Each of these pipe lines or conduits 25 has interposed therein a conventional check valve 28 which operates to prevent retrograde flow through the pipe line or conduit 25 with respect to the head 1.

As herein embodied, the inner faces of the grooves 23 are open but said open faces are closed by an annular member 29 snugly fitting within the peripheral portion of the cylinder or bore 12, as is clearly illustrated in the accompany drawings. This member 29 is fixed or non-rotatable with respect to the head 1. Any means may be employed to assure the effective locking of the applied member 29 and head 1 but, as particularly illustrated in Figure 1 of the drawings, such anchorage is secured through the medium of the suitably positioned conventional dowels 30.

The rotor R includes two plates 31 and 32, each of material thickness and of a radius to snugly engage within the member 29 but free to rotate therein. These plates 31 and 32 are arranged side by side about a common axis and have interposed therebetween an intermediate plate 33. The plates 31, 32 and 33, as herein disclosed, are effectively maintained in assembled relation by the headed members 34 freely

inserted through the outer plate 31 and intermediate plate 33 and threading into the second or inner plate 32.

It is believed to be obvious that means other than these headed members 34 may be employed for holding the plates 31, 32 and 33 in assembled relation. It is also preferred that the opposite faces of the intermediate plate 33 have disposed thereover gasket plates 35 of copper or other preferred material. As illustrated in the accompanying drawings, these gasket plates 35 are also held in position by the members 34.

The peripheries of the plates 31, 32 and 33 are provided therearound with the grooves 36 which register with the properly positioned grooves 31 provided in the inner wall of the applied member 29, said grooves 36 and 37 being V-shaped in form with their apices inwardly disposed and said grooves 36 and 37 snugly receive the segmental packing elements 38.

After the rotor R has been properly applied within the stator S, the outer end of the bore or cylinder 12 of the head 1 is closed, in the present embodiment of the invention, by a cap or head plate 39 removably held to the head 1 by the bolts 40 although, of course, other means for securing of this cap or head plate 39 may be used as preferred. As is clearly illustrated in Figure 1 of the drawings, the outer face of the plate 31 has close contact with the inner face of the applied cap plate or head 39 while the outer face of the plate 32 has close contact with the base wall 14 of the bore or cylinder 12. The plate 31 at its axial center is provided with an outstanding power take-off spindle or shaft 41 and the cap or head plate 39 carries the conventional ball bearing assemblies 42.

The face of the plate 31 opposed to the intermediate plate 33, or more particularly the adjacent gasket plate 35, has its central portion cut out to provide a chamber 43 which has its outer face closed by the intermediate plate 33, or more particularly one of the gasket plates 35. The intermediate plate 33 at its axial center is provided with an opening 44 into which threads an end portion of a tubular stem 45 open at both ends. As is clearly illustrated in Figure 1, this stem 45 extends axially through the hub sleeve 17 hereinbefore referred to and is of a length to extend a required distance beyond the outer end of this sleeve 17.

Rigidly mounted, as at 46, upon the outer or free end portion of this stem 45 is a circular plate 47 which snugly fits within the bore 3 of the sleeve 2 and, as illustrated in Figure 1, it is to be noted that the stem 45 is of such length to allow this plate 47 to be positioned between the ports 5 and 6 and 26 and 27. It is also to be noted that the stem 45 is of a major diameter materially less than the diameter of the bore of the sleeve 17 for a purpose to be hereinafter pointed out. The periphery of the plate 47 is provided therearound with a groove 48 which registers with a groove 49 in the adjacent inner face of the sleeve 2. These grooves 48 and 49 are V-shaped in cross section with their apices inwardly disposed and snugly receive the segmental packing members 50.

It is to be stated at this time that the stator S including the sleeve 2 and the member 29 is radially halved, as particularly illustrated in Figures 3, 6 and 8 of the drawings, to facilitate the assembly of the motor. The sections of the head 1 and the sleeve 2 are provided with the outwardly disposed butting flanges 51 with which

coact in a well known manner the holding members 52. It is believed to be apparent, however, that to all intents and purposes, insofar as the present invention is concerned, the head 1 and the sleeve 2, together with the member 29, can be considered as single units.

Disposed through the peripheral portion of the plate 31 and in communication with the chamber 43 are the outlet ports 53 herein disclosed as two in number and having their outer or discharge ends a substantially diametrically opposed. The inner portion of each of these ports 53 is enlarged, as at 54, to provide a housing which receives the inner end portion of a sliding abutment or vane 55 which moves outwardly and inwardly with respect to the periphery of the plate 31 through a suitably provided slot 56 extending through the peripheral portion of the plate 31 and open at both ends. This abutment or vane 55 snugly fits within the slot 56 and the outer end portion of this vane 55 is of such dimensions as to snugly and tightly engage, when extended, within one of the elongated channels or expansion chambers 57 provided in the inner face of the member 29.

In the present embodiment of the invention, these channels or chambers 57 are three in number and are of equal length. These channels or chambers 57 are also equidistantly spaced around the bore or cylinder 12 and one end 58 of each of the channels or chambers 57 constitutes a fixed abutment while the opposite end portion of each of the channels or chambers 57 has its base wall disposed substantially tangential to the inner open face of the channel or chamber 57 to provide a cam face 59 to effect the return movement of an extended abutment or vane 55 as the same travels along the cam 59 during the rotation of the rotor. It is preferred that the base wall or face of each of these channels or chambers 57 has disposed thereover the removable fiber strip 60, said strip extending from the fixed abutment 58 to substantially the outer end of the cam 59.

One of the grooves 23 hereinbefore referred to is coplanar with the applied plate 31 and, as is believed to be obvious in the assembled structure, such groove 23 constitutes an exhaust manifold. The cam end of each of the channels or chambers 57 is provided with an exhaust port 61 extending through the adjacent peripheral portion of the member 29 and having communication with the groove or exhaust manifold 23. Each of these ports 61 in the present embodiment of the invention is substantially midway of a cam 59 although, of course, this position may be varied within reasonable limits as the requirements of practice may deem best.

The wall of the chamber 43 adjacent to the enlarged portion 54 of each of the ports 53 is provided with a pocket 62 in which is tightly fitted a block 63. This block 63 is herein disclosed as held in place in a well known manner through the instrumentality of the locking key 63' coacting with the block 63 and an adjacent wall of the chamber 43. It will be obvious, however, that the block 63 may be otherwise held in place if preferred and for example by the elongated and radially opposed parallel rods 65 secured at their inner ends, as at 66, to the outer end of the block 63 and of a length to have close contact with a portion 67 of the wall of the chamber 43 opposed to said outer end of the applied block 63.

The block 63 has disposed therethrough a bore 75 the ports 69 is provided in its inner face with a

68, the outer end of which is in communication with the chamber 43 and the inner or inserted end being in communication with a port 69 formed in the plate 31 and which port is in communication with the enlarged portion 54 of a port 53. The block 63 at its inner or inserted end is provided at opposite sides of the bore 68 thereof with radially disposed slots 70 open at their outer ends and which provide for free passage of fluid under pressure through the cylinder 68 after the piston 71 working within the bore or cylinder 68 has been moved under fluid pressure beyond the inner ends of the slots 70.

With the piston 71 in this extended position, it is believed to be apparent that the fluid under pressure will flow through the bore or cylinder 68 beyond the cylinder 68 and out through the slots 70 into the port 69 and from the port 69 into the enlarged portion 54 of the port 53 and out through such port 53 into a groove or expansion chamber 23. During this period of flow, the adjacent abutment or vane 55 is sufficiently extended to offer no hindrance to the flow.

The piston 71, when free of fluid pressure from within the chamber 43, is normally maintained in its retracted position, as illustrated in Figure 6, by the expansible springs 72 encircling the rods 65 and butting the inner face of the block 63 and a cross member 73 carried by the outer or free end portion of the stem 74 carried by the piston 71.

One end portion of the cross member 73 is herein disclosed as having an offset extension or laterally disposed lug 75 through which is slidably disposed an end portion of a rod 76. This rod 76 outwardly of the extension or lug 75 has threaded or otherwise adjustably mounted thereon a stop 77 for contact with said extension or lug 75 whereby the movement of the rod 76 in one direction is limited by contact of said stop 77 with the extension or lug 75.

This rod 76 is of a length to have its end portion remote from the extension or lug 75 slidably disposed, as at 78, through a portion of the plate 31 and into the enlarged portion 54 of a port 53. The rod 76 at a desired point intermediate its end carries a surrounding collar 79 and interposed between this collar 79 and the extension or lug 75 is a coiled spring 80. This spring 80 encircles the rod 76 and is of a tension less than the tension of the springs 72, so that the rod 76 may move inwardly or rearwardly with respect to its port 53 without effecting corresponding movement of the cross member 73. This spring 80, however, is of sufficient tension to assure outward movement of the rod 76 in unison with the movement of the piston 71 under the pressure of the fluid within the chamber 43.

The extremity of the rod 76 within the enlarged portion 54 of the port 53 is operatively connected by a link 81 with the inner end portion of the adjacent sliding abutment or vane 55, so that as the rod 76 is moved outwardly, this abutment or vane 55 will also be moved outwardly so as to have proper engagement within the successive chambers 57. However, as such projected abutment or vane passes over a cam face 59, the spring 74 will allow such abutment or vane 55 to be forced back within the plate 31 but just as soon as the abutment or vane 55 passes over a cam face 59, it will be substantially instantaneously returned within the next chamber 57.

The plate 31 at a point intermediate each of

socket 82 intersecting the port 69 and in which pocket is snugly and slidably mounted a gate or slide valve 83. This valve 83 has a movement in a general direction axially of the plate 31 and when in one position intersects the port 69 to close the same against flow therethrough. This valve 83 at one end is provided with a laterally directed tappet 84. This tappet is of a length to snugly and freely extend through a suitably positioned opening 85 provided in the outer or closed side of the plate 31 and is intended to be received within one of a series of arcuate grooves 86 provided in the inner face of the cap or head plate 39. These grooves 86 are three in number and are equidistantly spaced around the plate 39 and concentric to the axis thereof.

Each of these grooves 86 is of a length to allow the valve 83 to be maintained in an open position during the travel of an extended abutment or vane 55 from substantially the fixed abutment 58 of a chamber 51 to the low part of the cam 59 at the opposite end of said chamber. Each of these arcuate grooves 86 has its base formed to provide the oppositely disposed cam faces 87, the low points of which are inwardly disposed with respect to the bottom or base of the groove 86.

The high point x and the low point y of each of these cam faces 87 are spaced apart in a direction lengthwise of the groove 86 a distance substantially equal to the diameter of the discharge end a of each of the ports 53 and each of these grooves 86 is of such length between the opposed inner low points y of the cam faces 87 at the opposite ends thereof and so positioned to allow for the desired opening movement of the valve 83 to commence at the time the forward portion of the discharge end of the port 53 passes beyond a fixed abutment 58 and the pitch of the cam face 87 is such that this valve 83 will be entirely opened with respect to its port 69 when the discharge end a of the port 53 has entirely passed beyond the fixed abutment 58.

The portion of the groove 86 between the cam faces 87 will allow the valve 83 to remain open until the extended extremity of the sliding abutment or vane 55 closely approaches the low point of the cam face 87, whereupon the second cam face 87 within the groove 86 will force the valve 83 into fully closed position with respect to the port 69. The distance z between the extremities of each pair of adjacent grooves 86 is such as to maintain the valve 83 in closed position until the tappet 84 of the valve 83 is allowed to enter the receiving end portion of the succeeding groove 86. The valve 83, as is clearly illustrated in Figure 4 of the drawings, has reciprocating movement within its pocket 82 in a direction lengthwise of the tappet 84 and this valve 83 is thrown into and maintained in open position, in the present embodiment of my invention, by the action of a spring 88 of requisite tension. As illustrated in Figure 4 of the drawings, this spring 88 encircles a pin 89 extending outwardly from an end portion of the gate valve 83 and extends within a suitably positioned opening 90 disposed through the intermediate plate 33. This spring bears against the gate valve 83 and against the gasket plate 35 at the side of the plate 33 remote from the gate valve 83. The gate valve 83 is provided with an outstanding pin 89 which is encircled by the spring 88 to increase the efficiency of said spring, said pin 89 freely moving within the opening 90.

It is believed to be obvious that while the rotor R is in rotation, the fluid within the channel or chamber 57 in advance of the extended abutment or vane 55 will be forced out through an exhaust port 61 into the associated exhaust manifold 23.

The sleeve 17, hereinbefore referred to, defines a central opening 92 through the second or inner plate 32 of the rotor R and which opening 92 provides communication with the central chamber 43 which, as illustrated in Figure 1, is closed by the intermediate plate 33 or more particularly the adjacent overlying gasket plate 35.

As the general constructions of the plates 31 and 32, together with the mechanisms arranged therein, are identical, it is believed that for clarity and brevity in disclosure, the corresponding features of these two plates 31 and 32 can be properly identified by the same reference characters. It is also pointed out that for all general practical purposes the closed side of the head 1 and the removable cap or head plate 39 are similar.

It is to be stated, however, that in practice 25 when the fluid pressure is directed within the central chamber 43 of one of the plates 31 or 32, such flow is cut off from the central chamber 43 of the second plate. In other words, each of the plates 31 or 32 may be considered as constituting a central operating unit effective when the other is ineffective and without any co-action therebetween. It will be obvious that the structure associated with one of the plates 31 or 32 is to effect rotation of the rotor R in one direction while the structure and arrangement associated with the second plate 31 or 32 is to effect rotation in the opposite direction and, of course, the necessary parts of the mechanisms carried by or associated with said plates 31 and 32 are in proper reverse arrangement. It is to be pointed out, however, that while the flow of the fluid under pressure into the chamber 23 of the plate 31 is through the tubular stem 45, the flow of such fluid into the central chamber 43 of the inner plate 32 is through the hub sleeve 17 which has its bore of sufficient diameter in excess of the major diameter of the tubular stem 45 to readily allow such flow.

In the embodiment of the invention as particularly illustrated in Figure 1, it is to be noted that when the fluid pressure is to the central chamber 43 of the inner plate 32 through the sleeve 17, the discharge of the fluid from the expansion chambers 57 will be through the sleeve 52 at the remote side of the plate 47 and vice versa. It is also believed to be apparent from the foregoing that when the fluid pressure is being delivered to the central chamber 43 of one of the plates 31 or 32, the sliding abutments or vanes 55 of the second plate 31 or 32 will be maintained in their fully retracted position, as illustrated in Figure 6, as, of course, said abutments or vanes 55 will only be extended when pressure is imposed upon the pistons 71 associated with such abutments or vanes 55.

The member 29 in advance of and closely adjacent each of the fixed abutments 58 is provided in its inner face with a radially disposed and relatively deep recess 97. This recess 97 is of desired length and is positioned in the same radial plane as the outlet ports 53 of the associated plate 31 or 32 and extends across the member 29 beyond opposite sides of the path of travel of said ports 53 when the rotor R is in action. Snugly fitting within this recess 97 is a packing

plate or block 98 which is maintained in close contact with the adjacent periphery of the plate 31 or 32, as illustrated in Figure 5, by an expandable coiled spring 99 interposed between the packing plate or block 98 and the base or inner end of the recess 97.

In assembling the halved parts of the head 1 and annular member 29, the same are effectively set and initially maintained in desired relative assembly by the conventional use of dowels 109, as indicated in Figures 3 and 8 of the drawings, although, of course, if desired other means may be employed for this purpose if deemed expedient.

While the invention as herein disclosed is particularly embodied in connection with fluid, such as oil under pressure, it is believed to be apparent that with but slight change it could be used in connection with compressed air or steam as the motive force and when so used the discharge manifolds 23 can deliver direct to the atmosphere or otherwise as may be preferred, as the particular arrangement of the pipe lines or conduits 25 herein disclosed will not be needed.

When a valve 83 is closed, there is a tendency to balance the pressure under the piston 71 but when this valve 83 is opened, the pressure will be allowed to go through the exit port 53 and while the valve 83 is open, the only way whereby the pressure may equalize itself under the piston 71 is for the load on the drive shaft to be too great for the amount of pressure being used. As one of the valves 83 is always in an open position, due to the timing cams, it is believed evident that there would be a constant flow of pressure in any one of the channels or chambers 57 at all times, thus assuring rotation of the rotor R since this rotation is caused by the thrust of the pressure between the fixed abutments 48 and the movable vanes 55. It is particularly pointed out that the only function of the piston 71 and the associated spring 72 is to withdraw a vane 55 back into the rotor when the reverse side is being used. For this reason each of the springs 72 is relatively weak as it does not have to perform any other function than to hold its associated vane 55 back in place against the centrifugal force of the trough on the reverse side of the unit.

In Figures 15 and 16 of the drawings is illustrated a modified structure as particularly pertains to the gate valves 83' and more particularly to provide means whereby the tension of the coiled spring 88' associated with each of said valves 83' may be regulated without disassembling the motor structure or with the same advantage any one of such springs may be readily removed and replaced.

In this modification of the invention, the suitably positioned opening 101 in which is received the spring 88' registers with an opening 102 which is disposed either through the plate 31' or 32' which is adapted to be brought into register with a suitably positioned opening 103 disposed through either the removable cap or head plate 39', as illustrated in Figure 15, or through the fixed head 1'. It is only required that there be a single opening 103 through either the cap or head plate 39' or the head 1' as the rotor R' can be readily rotated to bring the required opening 102 into register with the opening 103.

Insertible through an opening 103 for threading into a registering opening 102 is a plug 104 which provides an abutment for a spring 88'. By shifting this plug 104 lengthwise of the opening 102, the tension of the spring 88' may be reg-

ulated or controlled as desired and, of course, upon complete removal of a plug 104 a spring 88' can be readily removed and replaced. Normally each of the openings 103 is closed by a removable plug 105.

What I claim is:

1. A power unit comprising a cylinder, a rotor fitting in said cylinder, said rotor in its central portion having a chamber to receive a fluid under pressure and also having a plurality of ports spaced circumferentially therearound and opening and discharging through the periphery of the rotor, movable abutments carried by the rotor, there being one of said abutments adjacent to each of the ports, the encircling wall of the cylinder having a circumferentially arranged series of channels in the plane of the ports of the rotor, an end wall of each of the channels constituting a fixed abutment, the cylinder having an exhaust outlet in communication with the opposite end portion of each of said channels, each of the movable abutments upon outward movement extending within a channel to form an expandible chamber with the fixed abutment at one end of the channel, reciprocable pressure actuated elements connected with the abutments and operated by the pressure of the fluid within the chamber of the rotor to move the movable abutments outwardly to extend within the channels of the cylinder, the said elements being in the path of fluid travel from the chamber to the ports valves carried by the rotor and interposed between said pressure actuated elements and the ports for controlling the flow through the ports, means for maintaining each of the valves in open position while the adjacent movable abutment is extended within a chamber of the cylinder, and means for maintaining the valves closed during the period of time between adjacent ends of the channels of the receptacle.
2. A power unit comprising a cylinder, a rotor fitted within said cylinder, said rotor in its central portion having a chamber to receive fluid under pressure and also having a plurality of ports spaced circumferentially therearound and opening and discharging through the periphery of the rotor, movable abutments carried by the rotor, there being one of said abutments adjacent to each of the ports, with the abutment having a part extending within the port, a piston block within the port and having its bore open at both ends, a piston working in the bore of the block, said piston under the influence of the pressure of the fluid within the chamber of the rotor moving beyond the inner open end of the bore to allow the fluid under pressure to flow out through the port, the encircling wall of the cylinder having a circumferentially arranged series of spaced channels in the plane of the ports of the rotor, one end wall of each of the channels constituting a fixed abutment, the cylinder having an exhaust port in communication with the opposite end portion of each of the channels, an operative connection between the piston working in the bore of the block and the adjacent movable abutment for moving said abutment outwardly as the piston of the block is moved outwardly by the fluid pressure, and means for retracting said piston and abutment when the fluid pressure is ineffective.
3. A power unit as set forth in claim 2 wherein the operative connection between a piston and a movable abutment comprises a stem carried by the piston and extending within the pressure

chamber of the rotor, a cross member carried by the stem, an expansible medium interposed between the cross member and the block for retracting the piston, a rod within the pressure chamber and slidably extending within the port, an operative connection between the inserted end of the rod and the movable abutment, and an operative connection between said rod and the cross member to move the sliding abutment outwardly as the piston is moved outwardly by the pressure of the fluid within the pressure chamber.

4. A power unit as set forth in claim 2 wherein in the operative connection between a piston and a movable abutment comprises a stem carried by the piston and extending within the pressure chamber of the rotor, a cross member carried by the stem, an expansible medium interposed between the cross member and the block for retracting the piston, a rod within the pressure chamber and slidably extending within the port, an operative connection between the inserted end of the rod and the movable abutment, said rod being slidably disposed through the cross member, and an expansible member operatively engaged with the rod and the cross member to cause the movable abutment to move outwardly with the outward movement of the piston but allowing independent inward movement of the movable abutment.

5. A power unit comprising a cylinder, a rotor fitting in said cylinder, said rotor in its central portion having a chamber to receive a fluid under pressure and also having a plurality of ports spaced circumferentially therearound and opening and discharging through the periphery of the rotor, movable abutments carried by the rotor, there being one of said abutments adjacent to each of the ports, the encircling wall of the cylinder having a circumferentially arranged series of channels in the plane of the ports of the rotor, an end wall of each of the channels constituting a fixed abutment, the cylinder having an exhaust outlet in communication with the opposite end portion of each of said channels, each of the movable abutments upon outward movement extending within a channel to form an expansible chamber with the fixed abutment at one end of the channel, means operated by the pressure of the fluid within the chamber of the rotor to move the movable abutments outwardly to extend within the channels of the cylinder, valves carried by the rotor for controlling the flow through the ports, means for maintaining each of the valves in open position while the adjacent movable abutment is extended within a chamber of the cylinder, means for maintaining the valves closed during the period the outer or discharge ends of the ports are traveling between adjacent ends of the channels of the receptacle, a face of the pressure chamber of the rotor being open with the head of the cylinder closing said open face, a valve for controlling the flow through each of the ports mounted for back and forth movement, a laterally disposed tappet carried by each of the valves extending outwardly and freely through the adjacent portion of the rotor and disposed toward the head of the cylinder closing the chamber of the cylinder, the inner face of said head being provided therearound with a series of circumferentially spaced channels having their opposite end portions formed to provide cam faces, and means for moving the valve member to engage the tappet of the valve within the groove as the valve travels therealong, said valve in said adjustment

being open with respect to its port, contact of the tappet with the cam faces moving the valve into closed position with respect to its port, each of the grooves being of a length to allow the valve to be maintained in open position during the travel of the adjacent extended abutment from substantially the fixed abutment of a channel of the cylinder to the opposite end thereof, the high point of each of the cams of the groove being spaced from the low point in a direction lengthwise of the groove a distance substantially equal to the diameter of the discharge end of each of the ports.

6. A power unit, comprising a cylinder, a circular rotor fitting in said cylinder, said rotor having a chamber to receive a fluid under pressure and a fluid passageway leading from the chamber through the periphery of the rotor, the encircling wall of the cylinder having a circumferentially extending channel therein partly encircling the periphery of the rotor in the plane of said fluid passage, a radially movable abutment vane supported for movement transversely of the passage to an outward position in which it extends into said channel and inward from the channel in which it is disposed across and closes off the passage, a pressure responsive member within said passage adapted for movement in one direction under the action of fluid pressure from within said chamber, an operative coupling between said pressure responsive element and said abutment by which outward movement of the abutment into the channel is effected by the pressure responsive element upon movement of the element under pressure of fluid from the chamber, and an exhaust outlet in communication with an end of the channel, said passage opening into the channel between the abutment and the other end of the channel, said operative coupling between the pressure responsive member and the abutment being of a yieldable character whereby the abutment may be forced inwardly into position transversely of the fluid passage between the pressure responsive member and the outlet end of the passage while the pressure responsive member is maintained under the influence of fluid pressure from within the chamber.

7. A power unit, comprising a cylinder, a circular rotor fitting in said cylinder, said rotor having a chamber to receive a fluid under pressure and having a fluid passageway leading from the chamber through its periphery, the encircling wall of the cylinder having a circumferentially directed channel therein extending only part way around the cylinder and in the plane of the outlet end of the passageway to receive fluid therefrom, said channel having an exhaust outlet at one end, a radially movable abutment carried by the rotor adjacent the outlet end of the passageway, said abutment being movable across said passageway to close the passageway, the abutment being extensible outwardly into the channel and when so positioned opening the fluid passageway, said fluid passageway through a portion of its extent upon the side of the abutment opposite from the outlet of the passageway being formed as a piston cylinder having a lateral outlet, a piston in said cylinder movable under the action of fluid pressure from the chamber to open said lateral outlet for the establishment of uninterrupted fluid flow through the passage to the outlet end of the passage, and a coupling between the piston and the abutment by which the abutment is urged to move outwardly when the

piston is moved in a direction to uncover the lateral port.

8. A power unit as set forth in claim 7, in which the coupling between the piston and the abutment comprises two sliding parallel members and a spring connection between said parallel members whereby the abutment may move inwardly and outwardly while the piston is maintained in the lateral port uncovering position by the fluid pressure.

9. A power unit, comprising a cylinder, a circular rotor fitting in said cylinder, said rotor having a chamber to receive a fluid under pressure and a fluid passageway leading from the chamber through the periphery of the rotor, the encircling wall of the cylinder having a circumferentially extending channel therein partly encircling the periphery of the rotor in the plane of said fluid passage, a radially movable abutment vane supported for movement transversely of the passage to an outward position in which it extends into said channel and inward from the channel in which it is disposed across and closes off the passage, a pressure responsive member within said passage adapted for movement in one direction under the action of fluid pressure from within said chamber, an operative coupling between said pressure responsive element and said abutment by which outward movement of the abutment into the channel is effected by the 30

pressure responsive element upon movement of the element under pressure of fluid from the chamber, and an exhaust outlet in communication with an end of the channel, said passage opening into the channel between the abutment and the other end of the channel, a shut-off valve mounted for movement across the fluid passage along a path paralleling the axis of rotation of the rotor, and cam means for shifting 5 said valve to fluid passage closing position during such time as the abutment is retracted from said channel.

10. A power unit, comprising a cylinder, a circular rotor fitting in said cylinder, the rotor encircling wall of the cylinder having a circumferentially directed channel therein extending part way around the cylinder, the channel at one end having an exhaust outlet, the opposite end of the channel having a wall forming an abutment, 15 an abutment vane carried by the rotor for radial movement outwardly into said channel, means for effecting the radial movement of the abutment vane outwardly into the channel, means for introducing fluid into the channel between the abutment vane and the abutment wall, and a fiber strip lying in and covering the bottom surface of the channel from end to end of the channel and against which the outer edge of the 20 abutment vane has sliding contact. 25
